UNITED STATES PATENT OFFICE.

JOHN E. PFEFFER AND RAWSON H. LAYTON, OF CHICAGO, ILLINOIS.

EXPLOSIVE-ENGINE.

SPECIFICATION forming part of Letters Patent No. 761,539, dated May 31, 1904.

Application filed June 22, 1903. Serial No. 162,600. (No model.)

To all whom it may concern.

Be it known that we, JOHN E. PFEFFER and RAWSON H. LAYTON, citizens of the United States, residing at Chicago, county of Cook, State of Illinois, have invented a certain new and useful Improvement in Explosive-Engines; and we declare the following to be a full, clear, and exact description of the invention, such as will enable others skilled in the art to which it pertains to make and use the same, reference being had to the accompanying drawings, which form a part of this specification.

Our invention relates in general to engines, and more particularly to four-cycle explosive-engines particularly adapted for propelling motor vehicles and launches.

In single-cylinder explosive-engines only one explosion occurs during two revolutions of the driven shaft, and hence while sufficient power is developed to propel the vehicle on a level the power is inadequate to satisfactorily drive the vehicle upgrade. It is consequently desirable to employ double-cylinder engines for propelling automobiles, so that an explosion may occur during each revolution of the driven shaft. The employment of two cylinders has, however, in the engines as heretofore constructed practically necessitated the doubling of the mechanism and cost of a single-cylinder engine.

The primary object of our invention is to provide a double-cylinder engine of the four-cycle type which will be so compact in construction that it will require but little more metal in its manufacture and occupy only a slightly greater space in use than a single-cylinder engine.

A further object of our invention is to provide a double-cylinder four-cycle engine which will be comparatively simple in construction, inexpensive in manufacture, and efficient in use.

Our invention, generally described, consists in two aligned cylinders located on the same side of a driven shaft and mounted upon a two-part crank-casing through which the shaft extends, pistons in the cylinders rigidly united together, a single connecting-rod coupling both pistons to the same crank, separate

supply and exhaust valves for each cylinder, 50 valve-chambers communicating with the cylinders and having a plurality of openings of the same size leading thereto, some of said openings receiving conduits in which the supply and exhaust valves are located and other 55 of said openings being closed by caps, and valve-actuating mechanism whereby during each revolution of the crank-shaft an explosion occurs in one cylinder and an intake of motive fluid in the other, and during each return movement of the pistons an exhaust occurs from one cylinder and a compression of motive fluid in the other cylinder.

Our invention will be more fully described hereinafter with reference to the accompanying drawings, in which the same is illustrated as embodied in a convenient and practical form, and in which—

Figure 1 is an elevational view looking from the right in Fig. 2; and Fig. 2, a vertical sectional view taken on line 2 2, Fig. 1.

The same reference characters are used to designate the same parts in the two figures of the drawings.

Reference-letter A designates a crank-shaft, 75 and A' the crank, united to the shaft by crank-arms a'.

B designates a fly-wheel rigidly mounted upon the crank-shaft A.

C and C² designate a two-part crank-casing 80 through which the crank-shaft extends. The two parts of the crank-casing are provided with lateral extensions c and c², which form a chamber within which are located valve-actuating cams h' and h², fixed upon a 85 shaft G, extending through the chamber and journaled in bearings g g, supported by the crank-casing and preferably formed integral therewith.

The cam-shaft G has fixed thereto a gear-wheel G', which meshes with a gear-wheel g', fixed upon the crank-shaft A. The periphery of the gear-wheel G' contains twice as many teeth as the periphery of the gear-wheel g', thereby resulting in the cam-shaft being rotated only once during each two rotations of the crank-shaft.

Rigidly secured to the part C² of the crank-

casing are two alined cylinders D' and D², which are preferably formed in a single integral casting.

D designates a water-jacket surrounding the cylinders D' and D².

c is a cap for closing the end of the cylinder D'.

Located within the alined cylinders are pistons E' and E², rigidly united together and 10 preferably hollow. The diameters of the cylinders D' and D² are so related that the area of the annular piston E² is substantially equal to the area of the piston E'.

A connecting-rod F is united at one end to 15 the crank A' by a suitable bearing F', one part of which is formed integrally with the end of the connecting-rod and partially surrounds the crank, while the other part is detachably secured to the first part and surrounds the remaining portion of the crank. The opposite 20 end of the connecting-rod is pivotally united to a cross-rod f, rigidly supported at its opposite ends in the walls of the piston E'. Any suitable means may be utilized for uniting the 25 end of the connecting-rod to the cross-pin f'— such, for instance, as a split collar, such as shown in Fig. 2.

Valve-chambers d' and d² communicate with the cylinders D' and D² and are preferably 30 formed integral therewith. Passages d³ and d⁴ connect the valve-chambers with the corresponding cylinders. Each of the valve-chambers is provided with openings extending through the four walls thereof, in two of which 35 openings are secured couplings in which are seated the intake and exhaust valves and which communicate with supply and exhaust conduits. The openings in the back walls of the valve-chambers are provided with couplings 40 N' and N², in which are seated the intake-valves n' and n². Each intake-valve is provided with a rod extending through the coupling and surrounded by a spring n, engaging at its opposite ends a washer on the valve-rod 45 and the exterior of the coupling, thereby normally seating the intake-valve outwardly. The openings in the valve-chambers opposite to the intake-couplings are provided with exhaust-couplings, in which are seated exhaust- 50 valves L' and L², which are provided with valve-stems l' and l², mounted in tubular bearings m' and m², extending within the couplings M' and M². Coil-springs l surround the projecting ends of the valve-stems l' and l² and bear at their opposite ends upon washers fixed 55 on the valve-stems and against the exteriors of the couplings, thereby seating the exhaust-valves outwardly.

The openings through the walls of the valve-chambers located intermediate of the intake and exhaust couplings are closed by caps d d, thereby rendering it possible to locate the couplings in which the intake-valves seat in such openings, if desired, it being understood 60 that the openings through the valve-chambers

in which the couplings are secured and in which the covers d are secured are the same size.

Located in alinement with the valve-stems l' and l² are plungers H' and H², mounted to 70 reciprocate in bushings K' and K², located within tubular guides k' and k², formed integrally with the wall c' of the cam-shaft chamber. The ends of the plungers within the chamber are preferably provided with rollers, 75 which are engaged by cams h' and h², respectively, secured to the cam-shaft G. The cams h' and h² are located at one hundred and eighty degrees apart in order that the cycle of operation of the engines may be such that an explosion occurs in one cylinder simultaneously with the intake in the other and an exhaust in one cylinder simultaneously with the compression of the motive fluid in the other cylinder. 80

In order that the valve-stem l² may be retained in alinement with its actuating-plunger H², a bearing L is preferably provided, through which reciprocates the lower end of the stem. 90

The operation of our invention is as follows: With the parts in the position shown in Fig. 2 an explosion has just occurred in the cylinder D', which tends to rotate the crank-shaft in the direction of the arrow and draw into 95 the cylinder D² a charge of motive fluid through the intake-valve n'. During the return of the pistons to the position shown in Fig. 2 the cam h² forces the plunger K² outwardly, thereby unseating the exhaust-valve L² and permitting the exploded gases to discharge from the cylinder D', and during such exhaust from the cylinder D' it is evident that the motive fluid drawn into the cylinder D² by the previous cycle of operation is compressed. The charge in the cylinder D² is then exploded, which tends to drive the pistons 100 forward and draws into the cylinder D' a charge of motive fluid. The next back stroke of the piston compresses the motive fluid in 105 the cylinder D' and exhausts the exploded gas from the cylinder D², owing to the cam h' actuating the plunger K', and thereby unseating the exhaust-valve L'. 110

From the foregoing description it will be 115 observed that we have invented an improved double-cylinder explosive-engine of the four-cycle type comprising alined differential cylinders with which communicate valve-casings having a plurality of openings leading thereinto, in some of which openings are received 120 conduits containing the supply and exhaust valves, while the other of such openings are closed by caps, thereby rendering it possible to change the positions of the supply and exhaust conduits with respect to the valve-casings. It will also be observed that by providing a two-part crank-casing upon which the cylinders are mounted it is possible to decrease the weight of the engine by forming 125 130

the crank-casing of lighter metal than that necessarily used for the cylinders.

While we have described more or less precisely the details of construction, we do not wish to be understood as limiting ourselves thereto, as we contemplate changes in form, the proportion of parts, and the substitution of equivalents as circumstances may suggest or render expedient without departing from the spirit of our invention.

Having now fully described our invention, what we claim as new, and desire to secure by Letters Patent, is—

1. In an engine, the combination with integral aligned cylinders located on the same side of the shaft, the cylinders nearer the shaft being of greater diameter than the other cylinder, rigidly-united hollow pistons within the cylinders, a connecting-rod uniting the pistons to the driven shaft, laterally-projecting valve-chambers communicating with the cylinders, and having a plurality of openings through their walls, couplings engaging two of said openings in each valve-chamber, caps interchangeable with said couplings closing

the other openings in the valve-chambers, valves controlling the supply and exhaust of motive fluid to and from the valve-chambers and located in said couplings, and operating mechanism for controlling the valves actuated by the driven shaft.

2. In an engine, the combination with aligned cylinders located on the same side of the shaft, pistons within the cylinders, valve-chambers communicating with the cylinders and having a plurality of openings through their walls, couplings engaging two of said openings in each valve-chamber, caps interchangeable with said couplings closing the other openings in the valve-chambers, supply and exhaust valves located within the couplings, and means for actuating said valves.

In testimony whereof we sign this specification in the presence of two witnesses.

JOHN E. PFEFFER.
RAWSON H. LAYTON.
